(57) CLAIM

The ornamental design for a rechargeable battery for digital camera, as shown and described.

DESCRIPTION

FIG. 1 is a front, left side, top perspective view of a rechargeable battery for digital camera showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken line showings are for illustrative purposes only and form no part of the claimed design. The chain lines are provided to show the borderline between the claimed portions and the broken line portions which are not being claimed.
